APPARATUS FOR COATING PIPES AND THE
LIKEAlbert G. Perkins, Warsaw, N. Y., assignor to
Centriline Corporation, Ampere, N. J., a cor-
poration of Delaware

Application November 23, 1940, Serial No. 366,901

5 Claims. (Cl. 91—44)

This invention relates to certain new and useful improvements in apparatus for applying a protective coating of mortar or like material to the inner walls of steel pipe lines, conduits and the like.

It has for one of its objects to provide an apparatus of this character having a dispensing head for distributing the coating material by centrifugal force onto the pipe wall, and means located centrally of such head for imparting a continuous rotating motion to the material as it enters the plane of the head and simultaneously creating an outward pressure to force the mortar in a constant stream into the path of the distributing blades of the head.

Another object of the invention is to provide means effectually adjusting the flow of the mortar into the distributing head to properly distribute the amount of material desired over a particular portion of the pipe wall, as, for example, over the longitudinal row of rivet-heads along the jointed edges of the pipe-sections.

Other features of the invention reside in the construction and arrangement of parts herein-after described and particularly pointed out in the appended claims.

In the accompanying drawing:

Figure 1 is a side elevation of a pipe coating apparatus embodying my improvements, the same being shown in an operating position within a pipe line. Figure 2 is an enlarged, fragmentary, longitudinal section of the distributor head and associated parts. Figures 3 and 4 are enlarged cross sections taken in the plane of the correspondingly numbered lines in Figure 1. Figure 5 is a fragmentary side view of the ported or discharge end of the feed conduit.

Similar characters of reference indicate corresponding parts throughout the several views.

While my apparatus may be employed for coating different kinds of work, it has been primarily designed for treating the inner walls of pipe lines with a protective coating of a plastic-like material, such as concrete. The apparatus comprises generally a carriage 10 which is adapted to be propelled through the pipe 11 to be treated and which supports the various working parts of the apparatus including a feed hopper 12 for the coating material and a dispensing head 13 for delivering the material by centrifugal force onto the pipe wall.

Connecting the feed hopper with the dispensing head is a feed conduit 14 in which is arranged a conveyor screw 15 for propelling the material from the hopper to the dispensing head.

Adjacent its discharge end, the feed conduit is provided with an annular row of discharge ports 16, some of which are comparatively small in size while others indicated by the numeral 17 are much larger, as shown in Figures 3 and 5. By way of example, these larger ports are disposed at diametrically opposite sides of the conduit and substantially in line with the jointed portions of the pipe line containing the usual longitudinal rows of rivets 18, and at which zones a heavier or larger volume of material is desired. Surrounding the ported discharge end of the feed conduit, in concentric spaced relation thereto, is the dispensing head 13 which may be of any suitable construction, that shown in the drawing including radial blades 19 which receive the material from the ported end of the feed conduit and thence discharge it by centrifugal force onto the pipe wall. This dispensing head is shown as being driven by an electric motor 20 and belt 21 to the sleeve-like hub 22 of the head. It will be understood that a larger portion of the mortar will be delivered through the larger discharge ports 17 located in the top and bottom portions of the discharge end of the feed conduit 14 which will result in a correspondingly larger amount of mortar being delivered from the periphery of the head onto that portion of the pipe containing the rivets 18, as illustrated in Figure 3, thereby assuring a full and complete coating of the pipe along its jointed portions.

By preference, the ports 16, 17 are formed in a tubular section 23 which is telescopically fitted about the feed conduit 14 to form a continuation thereof and to rotate thereon so as to permit the adjustment of such tubular section to various positions for locating the larger ports 17 at such radial positions as the riveted joint lines or other unusual protuberances in the pipe section may determine. A pin and slot connection 24, 25 may be provided for limiting the extent of this adjustment and a suitable handle 26 or similar means is provided on the adjustable section 23 for conveniently adjusting it when desired.

Located at the discharge end of the feed conduit 14 and in the plane of the discharge ports 16, 17, is a rotatable device or rotor which functions to keep the mortar in a rotating motion during operation of the apparatus and also directs the mortar outwardly through the discharge ports. This device is preferably applied to the front end of the screw conveyor 15 to rotate therewith and it consists of a forwardly-flaring or bell-shaped body 27 whose rear or re-

duced end is substantially flush with the opposing shaft end of the feed screw 15 so as to permit a free flow of the mortar onto the same, while the front or flared end of such body terminates substantially flush with the forward edges of the discharge ports 16, 17. The diameter of the flared end of this body is slightly less than the inside diameter of the conduit-section 23 and as the mortar is forced by the conveyor screw onto the flared body, the surface of the latter acts to force the material radially outward toward the discharge ports. Applied to this body is a plurality of blades 28 which extend generally lengthwise thereof and obliquely to its axis of rotation, the blades being set into notches 29 formed in the body and having their outer edges parallel to the bore of the conduit section 23 and flush with the periphery of the flared end of such body, as shown in Figure 2. These blades, in addition to rotating and cutting into the material, force it forwardly as the flared surface of the body 27 directs it outwardly through the discharge ports.

I claim as my invention:

1. An apparatus for lining the inner walls of pipe lines, comprising a conduit adapted for communication at one end with a source of coating material, and open at its opposite end for the discharge of the material, a ported member adjustably mounted at the discharge end of said conduit for movement to different radial positions to control the desired angular flow of material therefrom, some of said ports being small and others comparatively large, and a rotary dispensing head disposed about and in operative communicating relation to said ports for receiving the material therefrom and directing it by centrifugal force onto the pipe wall.

2. An apparatus for lining the inner walls of pipe lines, comprising a conduit adapted for communication at one end with a source of coating material and open at its opposite end for the discharge of the material, a sleeve-like member applied to the discharge end of said conduit in enclosed relation thereto and having an annular row of discharge ports therein, some of said ports being larger than others, said member being adjustable to different radial positions about the conduit axis and having means thereon for moving it to such positions, and a rotary dispensing head disposed about said ports for receiving the material therefrom and directing it by centrifugal force onto the pipe wall.

3. An apparatus for lining the inner walls of pipe lines, comprising a conduit adapted for communication at one end with a source of coating

material and open at its opposite end for the discharge of the material, a sleeve-like member applied to the discharge end of said conduit in enclosed relation thereto and having an annular row of discharge ports therein, some of said ports being larger than others, said member being adjustable to different radial positions about the conduit axis and having means thereon for moving it to such positions, a pin and slot connection between said conduit and said ported member for preventing the axial movement of the latter and limiting its adjusting movements, and a rotary dispensing head disposed about said ports for receiving the material therefrom and directing it by centrifugal force onto the pipe wall.

4. An apparatus for lining the inner walls of pipe lines, comprising a feed conduit adapted for communication at one end with a source of coating material and provided at its opposite end with ports for the radial discharge of material therefrom, a rotary dispensing head disposed in operative relation to said ports for receiving the material therefrom and directing it by centrifugal force onto the pipe wall, and rotating means disposed in said conduit in the plane of its discharge ports for forcing the material therethrough, said means including a forwardly-flaring rotor against which the material is adapted to impinge and be forced outward through the ports, and blades applied to the periphery of said rotor in oblique relation to its axis, the outer edges of said blades being parallel to the contiguous inner wall of the conduit.

5. An apparatus for lining the inner walls of pipe lines, comprising a feed conduit adapted for communication at one end with a source of coating material and provided at its opposite end with ports for the radial discharge of material therefrom, a rotary dispensing head disposed in operative relation to said ports for receiving the material therefrom and directing it by centrifugal force onto the pipe wall, a conveyor screw in said conduit for forcing the material therethrough, and a rotor head applied to said screw to turn therewith in the plane of said discharge ports and including a forwardly-flaring body whose larger diameter terminates substantially flush with the forward edges of the discharge ports, and blades applied to said body and disposed obliquely to its axis of rotation for rotating the material and forcing it along the flaring surface of such body, said blades being coextensive with the flaring body and having outer edges parallel to the contiguous inner wall of the conduit.

ALBERT G. PERKINS.
